UNITED STATES PATENT OFFICE.

WILLIAM BENJAMIN TEALE, OF BIRMINGHAM, ENGLAND.

DESIGN FOR A DRIVING-CHAIN LINK.

SPECIFICATION forming part of Design No. 25,713, dated June 30, 1896.

Application filed March 28, 1896. Serial No. 543,587. Term of patent 7 years.

To all whom it may concern:

Be it known that I, WILLIAM BENJAMIN TEALE, a subject of Her Majesty the Queen of Great Britain and Ireland, residing at Birmingham, in the county of Warwick, England, have invented a new and original Design for Driving-Chain Links, of which the following is a specification.

Heretofore the links of driving-chains for cycles and for transmitting power for other purposes have usually been made with square edges next to the teeth of the driving-wheel and have therefore been liable to ride on the teeth when the chain has become slack.

Figure 1 is a view of the link complete. Fig. 2 is a cross-section of the same.

The leading features of my design consist in the links, having the shape shown on the accompanying drawings, the same being flat at the top with rounded ends around the eyes and a deep central recess at *a*, the inner edges of which next to the teeth of the driving-wheel

are rounded off, this rounded portion being continued for some little distance around the edges *b c* of the link.

My design for a chain-link has also an oval hole *d* between the two eyes, through which the joint-pins pass.

I claim—

The herein-described design for a chain-link consisting of the rounded ends having the eyes with the intermediate opening leaving the upper and lower bars connecting the eye portions, the recess in the lower part of the link and the rounded edge, the rounded portion extending along the depression and partly about the eye portions, substantially as described.

In witness whereof I have hereunto set my hand in presence of two witnesses.

WILLIAM BENJAMIN TEALE.

Witnesses:

CHARLES BOSWORTH KELLEY,
HERBERT WHITEHOUSE.
